UNITED STATES PATENT OFFICE

121,726

DESIGN FOR A BRASSIÈRE OR THE LIKE

Malvina Fieldseth, New York, N. Y., assignor to Maiden Form Brassiere Company, Inc., New York, N. Y., a corporation of New York

Application May 31, 1939, Serial No. 85,265

Term of patent 7 years

To all whom it may concern:

Be it known that I, Malvina Fieldseth, a citizen of the United States, residing at No. 430 West 24th Street, in the county of New York and State of New York, have invented a new, original, and ornamental Design for a Brassière or the like, of which the following is a specification, reference being had to the accompanying drawing, forming part thereof.

In the drawing:

The figure is a front view of a brassière in extended position, showing my new design; and, in this view, the dotted lines within the full lines denote stitching, while the other dotted lines denote the outline of the brassière.

While my design is shown in the drawing as applied to a brassière, it is to be understood that same is applicable to any lady's garment having a breast portion.

I claim:

The ornamental design for a brassière or the like, substantially as shown and described.

MALVINA FIELDSETH.
